UNITED STATES PATENT OFFICE.

JOHN A. EBERLE, OF ST. LOUIS, MISSOURI.

FOLDING GATE.

Application filed April 5, 1924. Serial No. 704,516.

This invention relates generally to folding gates, and particularly to a folding gate of the type ordinarily located at the top of a staircase to prevent children from falling down said staircase. Prior to this invention many gates for the purpose mentioned were produced which were composed of a plurality of bars pivoted together in a manner to provide a structure resembling lazy tongs. It was found that while a gate so constructed produced an ideal gate for the purpose, still it was not generally adopted for the reason that it lacked the required rigidity and durability to withstand the usage to which it was subjected. The purpose of the present invention is to produce a folding gate of the lazy tong type which is provided with reinforcing elements whereby said gate is supplied with the required rigidity and durability. Another object of my invention is to provide a gate of the type described with a simple means for locking said gate in an extended position, which locking means is so arranged that it may not be released by a child.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. I is a side elevation of a gate made in accordance with my invention, as said gate will appear when it is in use.

Fig. II is a cross section on line II-II of Fig. I.

Fig. III is an enlarged fragmentary view showing the improved locking device of my improved gate.

Fig. IV is an enlarged cross section showing the manner in which the spring snap of the locking device is secured in place.

In the drawing, A designates my improved gate, which in Figs. I and II is arranged in an opening between the members B, said members B being parts of a door frame, or uprights on a porch, or similar members which may be arranged adjacent to a staircase. The gate A comprises a pair of vertical bars 1 which are arranged in close proximity to each other and are

located adjacent to one of the members B, said bars 1 being hingedly secured to said member B by means of hinges 2. Pivotedly secured between the vertical bars 1 is a plurality of comparatively short members 3. 4 designates a pair of vertical bars which are located adjacent to the member B which is disposed oppositely to the member B adjacent to which the vertical bars 1 are arranged, said bars 4 also being arranged in close proximity to each other. The bars 4 are provided with a pair of members 5 which are pivotally secured between said bars 4 and are similar to the pivoted members 3 associated with the bars 1.

Interposed between the vertical bars 1 and 4 is a plurality of bars 6 which are arranged as shown in Fig. I and are pivoted together in a manner to produce a lazy tong structure. Certain of the bars 6 are pivotally secured to the pivoted members 3 and 5, and because said members 3 and 5 are in turn pivoted to the vertical bars 1 and 4 it is plain that a complete gate structure is produced which includes the lazy tong structure, the pivoted members 3 and 5 and the vertical bars 1 and 4. The operation of lazy tongs is very well known, and for that reason it is apparent that the gate illustrated in Fig. I of the drawing may be moved to a compactly folded position, in which position all of the bars making up said gate will be grouped in close proximity to each other adjacent to the vertical bars 1. It is also apparent that because of the hinges 2 the gate illustrated in Fig. I may be swung open in an unfolded condition.

The folding gate thus far described, as has already been stated, has been used heretofore, but said gate did not have sufficient rigidity to withstand the usage to which it was subjected. To overcome this deficiency I have devised a reinforcing means which will now be described.

7 designates a pair of reinforcing members which are pivoted to the lazy tong portion of the gate at points indicated by the reference character 8. Each of the reinforcing members 7 comprises a pair of bars which are arranged at opposite sides of the gate and are connected together intermediate of their ends by means of a comparatively short connecting bar 9. The bars comprising each individual reinforcing member 7 are pivoted to the gate, as stated, at the points indicated by the reference character

8, and the opposite ends of said bars are offset to provide said reinforcing member with a bifurcated end portion 10 (Fig. II). When a gate is completely assembled with 5 a pair of my improved reinforcing members arranged thereon the bifurcated end portions of said pair of reinforcing members are pivoted together, as shown in Figs. I and II. This permits the reinforcing members to be 10 folded together when the gate is moved to a folded position. It is apparent from the foregoing that the pivoted bars 6 making up the lazy tong structure of the gate are confined between the oppositely disposed 15 bars of the individual reinforcing members, and for this reason said lazy tong structure of said gate will not be permitted to bulge inwardly or outwardly, as would be the case if the reinforcing members were not present, 20 and as a result the gate is given much more rigidity and durability than it would possess in the absence of the reinforcing members. While the drawing shows a gate provided 25 with but a single pair of reinforcing members, it is apparent that if a very wide gate were produced it would be necessary to provide said gate with a plurality of reinforcing members, as it is not desirable to provide a gate with reinforcing members of such 30 length that they would extend beyond the top of the gate when said gate is in a folded position.

To secure my improved folding gate in an extended position across the top of a 35 stair case I provide one of the members B with an elongated strap 11. The strap 11 is secured at its upper and lower ends to the member B with which it is associated, and said strap is provided with a portion 12 which extends outwardly from said member 40 B. Arranged between the portion 12 of the strap 11 and the face of the member B is a complete ring 13, said ring being passed through said space between said member B and said portion 12 of the strap in such 45 manner that it may be moved vertically relative to said strap but may not be removed therefrom. The ring 13 is of such diameter that it may be passed downwardly 50 from the upper end of the vertical bars 4, as shown in Fig. I; and when said ring is in such position it is plain that the gate may not be folded or swung on its hinges 2. To prevent the ring 13 from being raised by a 55 child, I provide a spring snap 14 comprising a section of spring wire, the upper end of which is passed around a pin 15 which is located between the associated vertical 60 bars 4 (Fig. III). The section of spring wire comprising a spring snap 14 is interposed between the associated bars 4 and is provided with a lower portion 14', which is so located relative to the bars 4 that it is arranged immediately above the ring 13 65 when said ring is surrounding the bars 4 to

retain the gate in an extended position, and said portion 14' extends outwardly from said bars 4 such distance that the ring may not be raised when said spring snap is in its extended position. When it is desired 70 to raise the ring 13 to remove it from the bars 4 the spring snap 14 is depressed until it assumes the position in which it is shown by dotted lines in Fig. III, in which position the ring 13 may be freely raised without hindrance from said spring snap. To give 75 the spring snap 14 the required rigidity I form a plurality of tongues 16 in the oppositely disposed bars 4 between which said spring snap is arranged. The tongues 16 are bent inwardly, as shown in Fig. IV, to 80 positions where they contact with the spring snap whereby said spring snap is confined between said tongues and is prevented from moving at the point where it is engaged by 85 said tongues.

I claim:

1. A folding gate comprising diagonally arranged members each of which extends from the top of said gate to the bottom thereof, said diagonally arranged members being pivoted together to produce a lazy tong structure, and reinforcing means comprising a plurality of members arranged transversely of said diagonally arranged 90 pivoted members, said reinforcing members being pivoted together and pivoted to said diagonally arranged members, each reinforcing member comprising a pair of spaced apart bars between which said diagonally arranged members pass.

2. A folding gate comprising diagonally arranged bars pivoted together to produce a lazy tong structure, and reinforcing means comprising a pair of members arranged transversely of said diagonally arranged 105 pivoted bars, said reinforcing members being pivoted together and pivoted to said diagonally arranged bars, each reinforcing member comprising a pair of spaced apart bars 110 between which said diagonally arranged bars pass, and means connecting said spaced apart bars together.

3. A folding gate comprising a plurality of members pivoted to each other and adapted to be folded together, a slotted member at an end of the structure produced by said pivoted members, and means for retaining said folding gate in an extended position, said means comprising a strap secured to a 115 stationary element adjacent to said folding gate, and a looped member associated with said strap, said looped member being adapted to surround the upper portions of said slotted member which is arranged at an end of the foldable portion of the gate structure, and means comprising a spring snap for 120 retaining said looped member in such position.

4. A folding gate comprising a plurality 130

of members pivoted to each other and adapted to be folded together, a member at an end of the structure produced by said pivoted members, and means for retaining said 5 folding gate in an extended position, said means comprising a strap secured to a stationary element adjacent to said folding gate, and a looped member associated with said strap, said looped member being adapted 10 to surround the upper portion of said member which is arranged at an end of the foldable portion of the gate structure, means comprising a spring snap for retaining said looped member in such position, 15 and tongues formed integral with the member which supports said spring snap whereby said snap is retained in its proper position.

5. A folding gate comprising diagonally 20 arranged bars pivoted together to produce

a lazy tong structure, reinforcing means comprising a pair of members arranged transversely of said diagonally arranged pivoted bars, said reinforcing members being pivoted together and pivoted to said diagonally arranged bars, each reinforcing member comprising a pair of spaced apart bars between which said diagonally arranged bars pass, a vertical slotted bar at an end of the lazy tong portion of said gate, a strap secured to a stationary element adjacent to said gate, a ring associated with said strap, said ring being adapted to surround the upper portion of said vertical slotted bar, and means comprising a spring snap whereby 25 30 35 said ring is retained in such position.

In testimony that I claim the foregoing I hereunto affix my signature.

JOHN A. EBERLE.
